UNITED STATES PATENT OFFICE.

EDGARD FRANKIGNOUL, OF LIEGE, BELGIUM.

TUBING FOR BORING.

1,048,470.

Specification of Letters Patent. Patented Dec. 24, 1912.

Original application filed April 25, 1911, Serial No. 623,138. Divided and this application filed July 1, 1911. Serial No. 636,503.

To all whom it may concern:

Be it known that I, EDGARD FRANKIGNOUL, a subject of the Kingdom of Belgium, residing at 196 Rue Gretry, Liege, Belgium, have invented certain new and useful Improvements in Tubing for Boring; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 This is a division of an application filed by me under date of April 25th, 1911, Ser. No. 623,138.

This invention relates to tubular boring apparatus in which the tubular structure, 20 including a plurality of sections, is sunk into the soil by means of a succession of blows applied at the forward or directing end of the structure.

An object of my invention is to construct 25 the tubular structure in such a manner that the sections thereof may have telescoping action, one section following another as the structure is periodically sunk into the ground. By this construction the handling 30 and driving of a tubular structure of considerable length is facilitated, and the guiding of the structure in a predetermined position insured.

Further objects of my invention will appear from the following detailed description taken in connection with the accompanying drawing.

The tubular structure comprises a plurality of sections, and includes an advance section 1, and a following section 2, the length and number of which are dependent upon the desired length of the tubular structure 40 to be sunk.

In order that one section may follow another as they are driven into the soil, section 1 is provided with an external flange 4, at its upper end, while section 2 is provided with an internal flange 5, which latter when the section 1 has been driven sufficiently into

the soil, engages the flange 4 and is carried 50 with it.

The advance section 1 is provided with a shearing head 6, the upper portion of which forms an internal shoulder to receive a plug 7. The lower portion of the plug 7 is tapered as at 8 forming a trunco-conical portion, to facilitate entrance of the apparatus into the soil when being sunk. A succession of blows are imparted to the plug 7 by drop hammer or ram 9.

The ram 9 is guided by a rod 10 which passes through a central aperture in the plug 7. At the lower end of the rod 10 a pointed portion 12 is provided and such portion forms the entering and foremost guiding means of the apparatus.

The upper portion of the pointed portion 12 forms a shoulder 11 about the rod 10, and thus enables the plug 7 to be drawn from the tubular structure, after being sunk, 70 by raising the rod 10, the shoulder 11 engaging the tapered portion 8 of the plug 7 carrying the latter with it.

The operation of this device is as follows:—The apparatus is positioned where 75 it is desired to be sunk. The rod 10 then receives blows sufficiently to partly sink it, and in a desired line or direction. During such movement of the rod 10 the same is prevented from buckling by its passing 80 through the plug 7 and ram 9. The ram 9 is then brought into action and when the lower portion of the plug 7 contacts with the shoulder 11, the rod 10 is again advanced by blows imparted thereto. As the 85 advance section becomes sunk it draws with it each successive section by engagement of the coacting flanges. After having successfully started the advance section in the desired line of movement each succeeding section follows in its path.

I claim:

In a tubular boring apparatus, the combination with a plurality of telescopic boring tubes provided with coacting devices where- 95 by the sinking of one causes successive sinking of the remainder of the tubes, the tube to be initially sunk having a shearing lower

edge and an internal flange, a tapering plug fitting said tube and having a shoulder engaging said flange, an independently operable guiding rod extending through said plug and having a boring point disposed in advance of said plug, and a ram operable on said rod and arranged for engagement with said plug, substantially as described.

In testimony that I claim the foregoing as my invention, I have signed my name in presence of two subscribing witnesses.

EDGARD FRANKIGNOUL.
